HAND SAW

Wallace G. Ferry, Scotch Plains, N.J., assignor to Ferry Enterprises, Inc., Edison, N.J.

Filed Apr. 7, 1971, Ser. No. 132,254

Term of patent 14 years

Int. Cl. D8—03

U.S. Cl. D8—96

Fig. 1.

Fig. 2.

Fig. 3.

Fig. 4.

FIG. 1 is a front elevational view of a hand saw showing my design;

FIG. 2 is a right side elevational view thereof;

FIG. 3 is a top plan view thereof;

FIG. 4 is a bottom plan view thereof;

FIG. 5 is a front elevational view of a modified form thereof;

FIG. 6 is a right side elevational view thereof;

FIG. 7 is a top plan view thereof; and

FIG. 8 is a bottom plan view thereof.

The rear and left side of each hand saw have the same appearance as the front and right side, respectively, of each corresponding hand saw.

I claim:

The ornamental design for a hand saw, as shown and described.
